DIGITAL TEST PROBE

James A. Palmer, Willingboro, N.J., and Richard L. Longcoy, Lansdale, Pa., assignors to Nu-Concept Computer Company, Norristown, Pa.

Filed Apr. 13, 1970, Ser. No. 22,414

Term of patent 14 years

Int. Cl. D11—08

U.S. Cl. D26—1

FIG. 1 is a perspective view of a digital test probe showing our new design;

FIG. 2 is a side elevational view thereof;

FIG. 3 is a bottom plan view thereof;

FIG. 4 is a front elevational view thereof; and

FIG. 5 is an end view thereof.

We claim:

The ornamental design for a digital test probe, substantially as shown.
